(57) **CLAIM**

The ornamental design for an equipment case, as shown and described.

DESCRIPTION

FIG. 1 is a front perspective view of an equipment case, showing my design;

FIG. 2 is a perspective view thereof in the open position; and,

FIG. 3 is a rear perspective view thereof.

The devices shown in broken lines in FIGS. 1 and 3 are for illustrative purposes only and form no part of the claimed design.
